COVER FOR CENTRIFUGAL MACHINES EMPLOYED IN THE EXTRACTION OF SUGAR FROM SUGAR BEARING MATERIALS

Charles A. Olcott, West Milford, N. J.

Application March 27, 1939, Serial No. 264,402

5 Claims. (Cl. 210—63)

This invention relates to the automatic closing of machines and more particularly to covers for centrifugal machines employed in the extraction of sugar from sugar bearing materials.

An object of this invention is to increase the efficiency of centrifugal machines employed in the extraction of sugar from sugar bearing materials.

Another object of this invention is to prevent the dissipation of energy normally resulting from the operation of centrifugal machines.

Another object of this invention is to increase the ratio of operating to idle time of centrifugal machines.

In the processing of sugar from sugar bearing materials, such as magma and massecuite, the sugar bearing material is introduced into a centrifugal machine comprising a basket suspended from a shaft. After the desired amount of magma or other sugar bearing material is placed in the centrifugal, the shaft is rotated at relatively high speed. During this operation, the sugar which is precipitated in the magma is retained in the basket and removed from time to time. To secure the maximum yield of sugar, the magma introduced into the centrifugal is within a limited temperature range which is materially higher than the ambient. The heat developed in the centrifugal is utilized to maintain the magma within this range. It is essential, therefore, for maximum efficiency, that the heat produced by the centrifugal be not dissipated by the air currents which, if the centrifugal is uncovered, pass through the opening therein. Since the centrifugal has a small capacity and is charged and discharged frequently, it is desirable that the charging and discharging of the centrifugal be practised while the speed of the machine is reduced but not stopped. Covers have heretofore been proposed for closing the opening but their use has not been entirely satisfactory, since they tend to reduce production by increasing the time required for the charging and discharging operations. In the operation of most sugar centrifugals, covers have not been employed at all since the output of sugar per centrifugal for a given period of time was markedly reduced with manually operated covers. The amount of work for the operation required to control the opening and closing of the cover lengthened the time involved in the operating cycle of the centrifugal appreciably, resulting in a considerably lower output.

In accordance with this invention, the heat en-

ergy developed in the operation of the centrifugal is conserved by closing the opening of the centrifugal with a cover which is controlled in accordance with the speed at which the centrifugal rotates. When the centrifugal is rotated at a low speed to permit the introduction of the sugar bearing material and the discharging of the dried sugar therefrom, the cover is open. When the centrifugal operates at the high speed, the cover is closed. No time interval is required for the operation of the cover independent of the time involved in the other necessary operations of the centrifugal. The heat energy resulting from the operation of the centrifugal at high speed serves to heat the sugar bearing material. Further, this heat energy together with that imparted to the sugar bearing material before centrifuging is conserved and is not dissipated by the air currents which would flow through the opening if the centrifugal were not covered.

In a specific embodiment, the cover for the opening of a centrifugal machine is opened when the machine is operating at a low speed to introduce the sugar bearing materials or to withdraw the sugar therefrom and closed automatically when the machine is operating at high speed which prevails during the extraction of the sugar from the material. The closing and opening of the cover may be responsive to these two conditions or be controlled by changes in the speed of the mechanism employed for driving the centrifugal. Preferably, a pair of covers open and close the opening. These covers may be actuated by a system of bars controlled by a piston and spring. A cover for the closing of the opening in the bottom of the centrifugal may also be automatically controlled in a similar manner.

A more comprehensive understanding of this invention is obtained by reference to the accompanying drawings in which:

Fig. 1 shows top covers of a centrifugal in accordance with this invention and their controlling mechanism, partly in plan and partly in circuit schematic form;

Fig. 2 is a front elevation of a centrifugal, partly in section, including the top covers and part of the actuating mechanism shown in Fig. 1;

Fig. 3 is a front elevation of a portion of a centrifugal, partly in section, and including a bottom cover together with its actuating mechanism;

Fig. 4 shows an alternative form of control of the covers of this invention from that shown in Fig. 1.

The same numbers in the various views represent identical apparatus. In Figs. 1 and 2, a fixed casing 1 encloses a centrifugal basket 35 suspended therein and rotated through a shaft 4 by a motor 42 which is enclosed in housing 36. The motor and housing are supported by a superstructure, not shown, from which the shaft 4 and centrifugal basket 35 are suspended so that the centrifugal may rotate freely within the casing. Two top covers 2 and 3 employed for closing the opening of a centrifugal machine and all of the cooperating mechanism are in the closed position as shown in Figs. 1 and 2 for the high speed condition. For this condition, a manual switch arm 38 is operated to engage a contact 37. Current flows from the left hand side of power source 40 to a parallel circuit. One branch extends through a conductor 44 and the winding of solenoid 20, through conductor 45 to a junction point 47. A second branch extends through a conductor 46 and high speed winding 41 to the same junction point 47. Here the parallel circuits join and the circuit extends through contact 37, switch arm 38 and conductor 48 to the right hand side of power source 40. This drives the motor 42 at a high speed. The motor in turn rotates shaft 4 and centrifugal 35 at high speed. Current flowing through the winding of solenoid 20 actuates a solenoid shaft 21 against the pressure exerted downward by a spring 22, into its upper position as shown. The spring 22 is retained at its upper end against a valve cover 25 which is screwed to a valve body 24. At its lower end, valve rod 21 is secured to a piston 23 which is conditioned to move up and down within a hollow chamber 31 in the valve body 24, under the influence of current in solenoid winding 20 and the pressure exerted by spring 22 respectively.

When the piston 23 is in its upper position, as shown, air under pressure, from a source not shown, is supplied through a tube 19, a passage 49 in valve body 24, a notch 50 in piston 23, a channel 51 and a tube 18 connected to a chamber 52 in a cylinder 16. The air pressure in chamber 52 operating against a piston 17 maintains the piston 17 in its right hand position as shown. The piston 17 is in turn connected through a rod 32, a coupling 53 and pin 11 to a flat plate 29 which is rigidly held to a bar 5. Bar 5 is fixedly attached at its lower end to the cover 3 by means of bolts 28. At its upper end, bar 5 is conditioned to rotate in a horizontal plane about pivot 8, which is rigidly attached to a fixed plate 54. The cylinder 16 is rigidly secured through a bar 56 and a pin 13 to a plate 60 which is fixed in position by means not shown. A spring 15 is connected at its left hand end to the fixed plate 60 by means of a pin 14 and at its right end it is connected through a hole drilled in the flat plate 29 to the bar 5. As shown, for the high speed position, the spring 15 is distended, tending to open the covers which are held in position and prevented from opening by the pressure of the air against the piston 17 which preponderates over the tension of the spring.

When bar 5 is actuated to the right, as shown, for the high speed position, the cover 3 which is rigidly bolted to bar 5 is rotated as a unit with bar 5 in a horizontal plane about its center 8 to its extreme right hand position, sliding over the top surface of casing 1, to close the left hand portion of the circular opening in the casing above the open container. Movement of

the bar 5 also controls the operating of cover 2, simultaneously with the actuation of cover 3. Cover 2 is actuated to close the right hand portion of the circular opening in the following manner. As bar 5 is actuated to the right, it moves a bar 6, which is pivoted to the bar through pin 9. Bar 6 is pivoted in turn through pin 57 to the upper end of a bell crank lever 7. The bell crank lever 7 is pivoted through a pin 10 which is rigidly fixed in the top of casing 1. At its lower end, bell crank lever 7 is bolted by means of bolts 27 to the right hand cover 2. As bar 6 is actuated to the right, it rotates the upper end of the bell crank lever 7 to the right about its pivot 10, in turn operating cover 2 toward the left. The cover 2 slides also in a horizontal plane over the top surface of the casing 1 to close the right hand portion of the circular opening over the centrifugal. Two flat bars 58 and 59 are bolted to the cover 2. These bars serve to cover any opening which may exist in the joint between adjacent edges of the covers 2 and 3 when they are closed. The covers 2 and 3 together with the bars 58 and 59 effectively cover the opening in the casing 1 over the centrifugal and substantially prevent the flow of air through the top opening.

When the speed of the centrifugal is to be reduced for the loading or unloading operation, the switch arm 38 is actuated to engage a contact 39. The circuit through the high speed winding 41 of the motor 43 and the circuit through the winding of the solenoid coil 20, both of which were heretofore traced through contact 37, are broken when the switch arm 38 is disengaged from this contact. When the switch arm 38 engages the contact 39, a low speed winding 43 of the motor 42 is energized over a circuit which may be traced from the left hand side of power source 40, through conductor 46, a coil 43, contact 39, switch arm 38 and a conductor 48, to the right hand side of power source 40. As a result, the low speed winding of motor 42 is energized. The motor is operated at low speed, in turn imparting a low speed through shaft 4 to the centrifugal 35.

When the solenoid 20 is deenergized, spring 22, operating against valve cover 25, is effective to force solenoid shaft 21 and piston 23 connected thereto downward. Notch 50 in piston 23 is thus moved downward out of engagement with channel 49 in valve body 24, cutting off the supply of air under pressure to chamber 52 in cylinder 16. With the piston 23 in the lower position, the notch 50 engages channels 51 and 55 in valve body 24, providing a means by which the air under pressure in chamber 52 may escape into the atmosphere. This may be traced as follows: from chamber 52, through tube 18, channel 51 in body 24, notch 50 in piston 23, channel 55 in body 24 and a tube 26 to the atmosphere.

When the air pressure in chamber 52 is reduced, the piston 17 and bar 5 are actuated to the left by the tension in spring 15. The cover 3 is rotated to the left about pivot 8, sliding in a horizontal plane over the top surface of casing 1. The top of bell crank lever 7 is actuated to the left about pivot 10 by bar 6. The cover 2 rotates to the right about pivot 10 as a center, sliding over the top surface of casing 1. With cover 3 actuated to the left, and cover 2 actuated to the right, the opening over the centrifugal is uncovered for the loading or unloading operation.

A valve disc 33 is normally located in the bottom of the centrifugal basket 35. Fixedly attached to the disc 33 is an eyelet bolt 64 by means of which the disc may be removed to withdraw the sugar from the basket in a well known manner. For this purpose, a hook 65 of a chain 34, which is lowered in the centrifugal basket 35 at the time of the removal of the sugar through the bottom, is attached to the eyelet bolt 64 and subsequently hoisted by means of a windlass, handle or other device, not shown, over a pulley 66 fixedly attached to a support 67. The dotted configuration of the valve disc 33 and eyelet bolt 64 designated as 33' and 64' respectively in Fig. 2 shows their position when the sugar is removed through the bottom of the basket. Steam is supplied to the centrifugal by means of a pipe line 30.

Fig. 3 shows an arrangement for removing the sugar through an opening in the bottom of the centrifugal machine and for substantially preventing the flow of air currents through the opening when the machine is operating at high speed. This system operates so that the bottom of the centrifugal is opened when the machine is operated at slow speed, but closed when rotated at high speed. For the high speed condition, air from a solenoid valve, controlled through the speed changing switch as described for the devices shown in Figs. 1 and 2, is admitted through a tube 312 to a hollow chamber 313 in a cylinder 311. The air actuates a piston 310 of the cylinder 311 to the right against the compression of a spring 309 which is confined between the right hand surface of the piston and an abutment 314 at the right hand end of the cylinder. The piston and a rod 315, integral therewith, communicate a right hand motion through a pin 317 to a rod 306. The rod 306 is connected through a pin 305 to a right angle arm 304 which is integral with a door 302. Door 302 is a flat circular disc having the arm 304 welded in the middle thereto at right angles to the surface thereof. The base of arm 304 adjacent to the disc is pivoted to a fixed horizontal shaft 316. The cover has a limited rotary motion about said shaft in response to the reciprocal action of the piston. Two positions of the cover and connecting linkage are shown. The position indicated by solid lines is the extreme right hand position of all of the moving parts. It corresponds to the high speed condition of the motor and centrifugal. For this condition, the cover is closed as indicated. The position shown in dotted lines of the door 302', arm 304' and rod 306' indicates an intermediate position assumed by the cover as the piston and linkage move to the left under the influence of spring 309. As the air under pressure is evacuated from the chamber 313, in the manner heretofore described, the cover is gradually opened so that the centrifugal may be discharged.

Fig. 4 shows an alternative embodiment for the manual switch 38 of Fig. 1 for controlling the operation of the solenoid valve in response to changes in driving speed. Instead of employing manual switch 38 to control the solenoid 20 of Fig. 1 to operate the covers 2 and 3 of Fig. 1, or the door 302 of Fig. 3, the solenoid may be independently controlled automatically by the centrifugal arrangement shown in Fig. 4. A spring 407 is attached to the shaft 4 by means of screws 408. To the free end of the spring 407 is fastened a weighted sphere 401. As the shaft 4 is rotated, the spring 407 is actuated by cen-

trifugal force so that the free end tends to move from the shaft. A contact 402, mounted on the spring 407, engages a fixed annular contact 403 mounted in a fixed housing or guard 404. The annular contact 403 is so disposed in the housing 404 that when the spring 407 is extended in its extreme outward position due to centrifugal force, the contact 402 engages the annular contact 403 continuously and regardless of the position of the contact 402 with relation to the fixed housing or guard 404. The housing or guard covers the shaft about the rotating device and is held in position by means not shown. The fixed end of the spring is connected internally by means not shown to a commutator 406 which engages a brush 405. When the speed of rotation of the shaft is sufficiently high, contacts 402 and 403 close, completing a circuit through power source 409 to energize the solenoid winding 20 as shown in Fig. 1, and the covers close. When the speed is reduced, the contacts 402 and 403 open, deenergizing the solenoid winding, and the covers open.

While preferred embodiments of this invention have been illustrated and described, various modifications may be made therein without departing from the scope of the appended claims.

What is claimed is:

1. A centrifugal separator comprising a casing, a rotatable basket within said casing, said casing having an opening therein affording access to said basket, a cover for said opening, driving means for rotating said basket at high speed, a controller for engaging and disengaging the high speed drive, a power-operated device for positioning said cover and means connected to said power-operated device and responsive to the positioning of said controller to high speed drive for initiating the closing of said cover by said device, said last-mentioned means being responsive to the positioning of said controller to disengage the high speed drive for initiating the opening of said cover by said device.

2. A centrifugal separator for the extraction of sugar from sugar magma or the like comprising a casing, a rotatable basket within said casing, said casing having an opening therein to permit loading and unloading of said basket, a removable cover for said opening, a power-operated device for positioning said cover, driving means for rotating said basket at high speed, means operatively connected to said power-operated device and responsive to the high speed operation of said driving means for initiating the closing of said cover by said device, and means responsive to the deceleration of said driving means for initiating the opening of said cover by said device.

3. A centrifugal machine for the separation of sugar from sugar bearing materials comprising a rotatable basket, a casing enclosing said basket and having an opening for permitting loading and unloading of said basket, a cover for said opening, a power mechanism for opening and closing said cover, driving means for rotating said basket, means for controlling the speed of operation of said driving means, said control means being operable to one condition to effect high speed driving of said basket, said control means being operable also to another condition to effect low speed driving of said basket, means operatively connected to said power mechanism and actuated in response to operation of said control means to said one condition for initiating automatic closing of said

cover by said power mechanism, and means actuated in response to operation of said control means to said other condition for initiating automatic opening of said cover by said power mechanism, whereby said basket is automatically enclosed during high speed operation to preclude escape of heat therefrom and injection of foreign matter by air currents otherwise prevailing.

4. A centrifugal machine for the separation of sugar from sugar bearing materials comprising a rotatable basket, a casing enclosing said basket and having an opening therein for permitting loading and unloading of said basket, a cover for said opening, a power-operated device controllable to open and close said cover, driving means for rotating said basket, means for controlling the speed of operation of said driving means, said control means being operable to one condition to effect high speed driving of said basket, said control means being operable also to another condition, means controlled by the speed of said driving means and actuated in response to the attainment of a predetermined speed following operation of said control means to said one condition, means responsive to actuation of said controlled means and operatively

connected to said device for initiating automatic closing of said cover by said device, and means operatively connected to said device and responsive to the attainment of a predetermined speed following operation of said control means to said other condition for initiating automatic opening of said cover by said device.

5. A centrifugal machine for the separation of sugar from sugar magma, or the like, comprising a rotatable basket for containing the material to be centrifuged, a casing enclosing said basket and having an opening therein for affording access to said basket, a cover for said opening, driving means for rotating said basket, said driving means being operable at either of two substantially different speeds, means responsive to the operation of said driving means at the higher of said speeds, cover closing means connected to be actuated by said responsive means for closing said cover over said opening, means responsive to the operation of said driving means at the lower of said speeds, and cover opening means connected to be actuated by said last-mentioned means for removing said cover from said opening.
